FIXTURE FOR ASSEMBLING ARTICLES

John L. Baum, Baltimore, Md., assignor to Western Electric Company, Incorporated, New York, N. Y., a corporation of New York

Application March 18, 1944, Serial No. 527,113

1 Claim. (Cl. 113—99)

This invention relates to fixtures for assembling articles, particularly to fixtures for assembling fabricated gear blanks, and has for its object the provision of new and improved fixtures for assembling articles.

One fixture embodying the invention comprises a hard steel plate having a flat upper surface, a plurality of jaws arranged symmetrically around the plate, means for moving the jaws to cause them to engage and position a gear blank positioned on the plate, a pair of posts extending upwardly from the plate, a cross bar movably supported on the posts, means for raising and lowering the cross bar, and a chuck carried by the cross bar designed to hold a gear hub blank accurately aligned with a gear blank held within the jaws, whereby the gear blank and the hub blank may be welded together in a predetermined relationship.

A complete understanding of the invention may be obtained from the following detailed description of a specific embodiment thereof, when read in conjunction with the appended drawings, in which

Fig. 1 is a perspective view of a fixture embodying the invention with portions thereof broken away.

Fig. 2 is a vertical sectional view of the fixture.

Fig. 3 is a fragmentary horizontal sectional view of the fixture taken along line 3—3 of Fig. 2, and

Fig. 4 is an enlarged perspective view of an element of the fixture.

Referring now to the drawings, a flanged annular plate 10 (Fig. 1) secured to a flanged base plate 11 is provided with three oblong, radial guide slots 12—12, so positioned that the longitudinal axes thereof form 120° angles with each other. The upper surface 14 of the plate 10 is ground perfectly flat so that it lies in a horizontal plane.

The plates 10 and 11 form a chamber 13 (Figs. 1 and 2) therebetween in which is rotatably mounted a scroll gear 15 having a ring gear 16 formed thereon. The ring gear 16 meshes with a pinion 17 mounted in a bore 18 formed in the flanges of the plates 10 and 11. The pinion 17 has an aperture 19 formed therein into which the end of a wrench (not shown) may be inserted to rotate the pinion 17 and thereby rotate the scroll gear 15.

A plurality of jaws 21—21 (Figs. 3 and 4) having guiding grooves 22—22 formed therein are slidably secured in the guide slots 12—12 by tongues 23—23 projecting into the slots 12—12.

The jaws 21—21 have gear teeth 24—24 (Fig. 2) formed thereon which mesh with the scroll gear 15. A plurality of curved gripping surfaces 25—25 formed on the jaws 21—21 are spaced equal distances from the center of the plate 10. The gripping surfaces 25—25 project above the surface 14 of the plate 10 and are moved simultaneously at equal rates of speed toward or away from the center of the plate 10 by the scroll gear 15 when the latter is rotated, depending upon which direction the scroll gear is rotated.

A pair of standards 30—30 (Figs. 2 and 3) are welded to the plate 10 upon opposite ends of a diameter of the plate, and a pair of blocks 32—32 having tapped vertical bores 35—35 formed therein are welded to the upper ends of the standards 30—30. Each of the standards 30—30 has a dovetail groove 31 (Fig. 3) formed therein, and a cross bar 36 (Fig. 2) has a pair of dovetailed arms 37—37 depending therefrom and fitting slidably within the grooves 31—31. The cross bar 36 is adjustably supported upon the standards 30—30 by a pair of bolts 38—38 threaded into the tapped bores 35—35 and provided with knurled heads 39—39. A pair of collars 40—40 (Fig. 2) secured to the bolts 38—38 rotatably secure the unthreaded upper portions of the bolts 38—38 in a pair of holes 41—41 extending through the cross bar 36.

30 A universal chuck 45 (Figs. 1 and 2) of conventional design, is secured to the cross bar 36 coaxially with the plate 10. Jaws 46—46 of the chuck 45 extend beyond and are engaged by a threaded cap 47, which may be turned to open or close the jaws. The cross bar 36 and the chuck 45 carried thereby may be moved toward or away from the plate 10 by screwing the bolts 38—38 farther into or out of the tapped bores 35—35.

In the operation of the fixture described hereinabove, a cylindrical hub blank 50 (Fig. 2) is inserted in the jaws 46—46 and is secured therein by turning the cap 47. A gear blank 51 is then placed upon the flat upper surface 14 of the plate 10 and the pinion 17 is rotated by a wrench (not shown) to move the jaws 21—21 toward the center of the plate 10 until the gripping surfaces 25—25 firmly secure the gear blank 51 concentrically with respect to the plate 10, and center the gear blank beneath the hub blank 50. The bolts 38—38 are then actuated to force the hub blank 50 against the gear blank 51. While the hub blank 50 and the gear blank 51 are thus securely held in concentric relationship, the hub blank is welded to the gear blank. After the welded assembly has cooled, the chuck 45 is oper-

ated to unclamp the hub blank 50 and the bolts 38-38 are turned to raise the chuck 45 away from the hub blank. The jaws 21-21 are then withdrawn from engagement with the welded gear blank and the welded assembly is removed from the fixture, after which the above described operation may be repeated.

The above described fixture is adapted to quickly and accurately align hub and gear blanks and to securely hold such blanks in aligned relationship while they are being welded and while they are cooling thereafter.

What is claimed is:

In an article assembling fixture, a horizontally disposed circular plate having a level upper surface and also provided with a plurality of radial slots, a plurality of jaws having shanks formed thereon, said shanks being slidably positioned in said slots, means for simultaneously moving said

jaws toward and away from the center of said plate to secure a gear blank concentrically on said plate, a pair of standards having dovetail grooves formed longitudinally therein and also being provided with a pair of longitudinal tapped bores in ends thereof, said standards being secured vertically on said plate, a cross bar having dovetailed arms which fit slidably into said dovetail grooves, a chuck secured to said cross bar in a position concentric with said circular plate and designed to hold a cylindrical blank, and a pair of bolts designed to be screwed into said tapped bores for moving said cross bar and said chuck toward said plate to force a cylindrical blank held by said chuck against a gear blank secured on said plate concentrically with the cylindrical blank.

JOHN L. BAUM.
